US0D1000609S

(12) **United States Design Patent** (10) **Patent No.:** **US D1,000,609 S**
Jansson (45) **Date of Patent:** **** Oct. 3, 2023**

(54) **TUBE DEVICE**(71) Applicant: **RoddyMedical, LLC**, Wauwatosa, WI (US)(72) Inventor: **Kyle Jansson**, Brookfield, WI (US)(73) Assignee: **RoddyMedical, LLC**, Milwaukee, WI (US)(***) Term: **15 Years**(21) Appl. No.: **29/850,795**(22) Filed: **Aug. 23, 2022****Related U.S. Application Data**

(62) Division of application No. 29/757,577, filed on Nov. 6, 2020, now Pat. No. Des. 969,311.

(51) **LOC (14) Cl.** **24-02**(52) **U.S. Cl.**USPC **D24/128**; D8/356

Primary Examiner — Natasha Vujcic*Assistant Examiner* — Gilbert B Ford(57) **CLAIM**

The ornamental design for a tube device, as shown and described.

DESCRIPTION

FIG. 1 is a perspective view showing a tube device embodying the new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings illustrate portions of the tube device which form no part of the claimed design.

1 Claim, 5 Drawing Sheets(56)
